UNITED STATES PATENT OFFICE.

CHARLES J. AHRENFELDT, OF NEW YORK, N. Y.

DESIGN FOR A CHINA PLATE.

40,860.

Specification for Design.

Patented Sept. 6, 1910.

Application filed February 1, 1909. Serial No. 475,529. Term of patent 7 years.

To all whom it may concern:

Be it known that I, CHARLES J. AHRENFELDT, a citizen of the United States, and a resident of New York city, in the county of New York and State of New York, have invented a certain new, original, and ornamental Design for China Plates or Similar Articles, of which the following is a specification.

In the accompanying drawing, the figure is a plan showing the design on the plate.

The design illustrated is embodied in a plate or the like, the edge portion or flange of which is provided with a plurality of sets of raised or corrugated portions 1, separated by depressions 2. The corrugated portions are

curved and disposed at an angle to the radial line of the plate as shown, and gradually increase in height toward the outer edge of the plate.

The numeral 3 indicates a double line parallel to the scalloped edge of the plate, and the outer ends of the corrugations are defined by the scallops of the edge.

What I claim is:—

The ornamental design for a china plate or similar articles, substantially as shown and described.

CHARLES J. AHRENFELDT.
